CLAIM

The ornamental design for a spa step, as shown and described.

DESCRIPTION

FIG. 1 is a perspective view of applicants' spa step; FIG. 2 is a side elevation view of the spa step as shown in FIG. 1, the opposite side view being a mirror image thereof; FIG. 3 is a top plan view of the spa step shown in FIG. 1; FIG. 4 is a front elevation view of the spa step shown in FIG. 1;

FIG. 5 is a perspective view of the step support of the applicant's spa step; and,

FIG. 6 is a side elevation view of the step support of the applicant's spa step.

The broken line disclosure is for illustrative purposes only and forms no part of the claimed design.
